UNITED STATES PATENT OFFICE.

HECTOR LE DOUX, OF BOSTON, MASSACHUSETTS, ASSIGNOR TO THE STAFFORD COMPANY, OF READVILLE, BOSTON, MASSACHUSETTS, A CORPORATION OF NEW JERSEY.

SELVAGE-FORMING DEVICE.

1,344,413.

Specification of Letters Patent. Patented June 22, 1920.

Application filed March 18, 1920. Serial No. 366,814.

To all whom it may concern:

Be it known that I, HECTOR LE DOUX, a citizen of the United States, residing at Readville, Boston, in the county of Suffolk, 5 State of Massachusetts, have invented a certain new and useful Improvement in Selvage-Forming Devices, of which the following is a specification, reference being had therein to the accompanying drawings.

10 The invention has relation to a class of devices designed for employment in looms and intended to secure straight, uniform, and perfect selvages upon the cloth woven therein. These devices have for their special 15 function to act during the weaving operations to prevent the return bends of weft or filling at the opposite selvages of the cloth from drawing in the marginal warp thread or threads in such manner as to 20 render the edges of the cloth irregular.

The invention consists in devices of the said class of the novel and improved construction and combination which I will now proceed to describe, and which is particularly pointed out in the claims at the close 25 of this specification.

The invention is illustrated in the accompanying drawings in which latter,—

Figure 1 is a side elevation of a loom-temple of usual construction having my invention applied thereto.

Fig. 2 is a plan view of the parts shown in Fig. 1.

Fig. 3 is a rear elevation thereof.

Fig. 4 is a detail view.

Having reference to the drawings, *a* represents the slide-bar of the temple, *b* the temple-stand adapted to be fixed upon the loom-frame and having front and rear guides *c* and *d* in which the said slide-bar is mounted with capacity to slide endwise, as usual; *e* is the spring by which the slide-bar and its roller-head *f* are kept normally in their rearward position and are returned 45 to such position after being pushed forward by contact of the advancing lay with lug *g* extending down from roller-head *f*; and *h*, Fig. 3, is one of the bur rolls within the roller-head *f*. The illustrated temple is one 50 furnished with two bur rolls. At *i* is the cover or top of the rear guide *d*.

It is to be understood that in practice devices of the nature to be described hereinafter are employed at each selvage of the 55 cloth.

Referring now more particularly to the selvage forming device, 1 is a vertically-swinging arm, pivoted at its forward end to an upstanding support 3 rising from the slide-bar *a* and located forward of the rear 60 guide *d*, said arm having at its rear end a downturned tapering point 1^a occupying, when said arm is lowered, a position closely adjacent the outer end of the bur roll *h*, at a slight distance to the rear of the cloth-making line or fell. If desired, this position may be just outside of and closely adjacent to the selvage warps, in such relation to said warps that the weft-thread or filling will be bent around the point 1^a as the shuttle 65 reenters the shed. With such arrangement, the inward pull of the weft yarn, ordinarily taking effect upon the selvage warps and tending to make the selvage irregular, is borne by the point 1^a so that the selvage 70 warps are freed entirely therefrom. If preferred, the point may be adjusted to enter between the warp threads at the selvage, with substantially the same results.

The construction of the swinging arm 1, 80 and the mode of mounting the same, may vary in practice. In the present instance, the support 3 upon the slide-bar *a* has fixed thereto the pivot 4, and for convenience in construction and adjustment, the arm 1 is 85 made in two parts, namely the main portion which is formed with the point 1^a, and the bearing member 5 which has a socket within which the forward end of said main portion is secured by a clamping screw 6, 90 the said member 5 being mounted upon pivot 4. The said main portion may be adjusted longitudinally relative to said socket-member to give the downturned point 1^a a working position at the desired distance 95 rearward of the surface of the bur roll *h*, and it may be adjusted by turning it within the socket so as to shift the downturned point 1^a laterally inward or outward. This turning of the arm within the socket, for 100 the lateral adjustment of the point, is provided for by making the socket circular in cross-section, and either making portion 1 of the arm of round stock, or forming it with a rounded end-portion adapted to fit 105 into the said pocket.

The socket-member 5 extends rearwardly from its pivot 4 over the cover or top *i* of the rear guide *d* for the temple-bar *a*, and interengagement between said socket-mem- 110

ber and said cover or top is utilized for the purpose of swinging the arm 1 upward as the movable part of the temple is driven forward by the pressure of the lay against the lug *g* of the roller-head. In the illustrated construction the socket-member 5 is formed with a downwardly and rearwardly extending finger 5^a, adapted to bear upon the said cover or top. This finger is formed 10 with a cam-shaped portion 5^b, which, when the movable part of the temple is rearward, drops at the rear of the cover or top *i*, but when the movable part of the temple is driven forward by the lay the said cam-shaped portion 5^b rides up onto the top of the said cover or top, thereby raising the arm, and withdrawing the point 1^a from the loop of weft or filling formed around it and the adjacent warp-thread or threads. 15 To facilitate this action, the cover or top *i* is formed with an incline *i'*, which enables the cam-shaped portion 5^b to ride up onto the said cover or top more easily.

A vertical channel or groove *j* is formed 20 in the rear face of the roller-head to accommodate the point 1^a, so that it will not be struck by the reed carried by the lay, or be damaged or displaced by accidental contact with the shuttle. The inner wall of 25 said groove may be utilized to lend lateral support to the swinging arm 1 to resist the inward pull of the weft thereon. The width of the channel or groove is sufficient to permit the point to be adjusted laterally as de- 30 scribed above.

Gravity alone may be depended upon to 35 keep the arm and point down in the normal working position occupied by them in the drawings, and to return them thereto after 40 having been raised, or a spring *k* may be employed to aid gravity in so doing.

What is claimed as the invention is,—

1. The combination with a roller temple comprising a spring-actuated slide-bar and roller-head adapted to be moved forward 45 by the lay in beating-up, and a temple-stand having a covered rear guide for the slide-bar, of a vertically swinging arm having a pivotal mounting in connection with the slide-bar at a point forward of the said 50 guide, and a downturned point at its rear end working at the rear face of the temple-head, said arm raised by engagement with the cover or top of the said guide in the forward movement of the slide-bar and 55 temple-head so as to disengage the point from the threads of the fabric being woven.

2. The combination with a roller temple having its head channeled vertically adjacent the outer end of the bur roll, of a selvage- 60 protector arm receiving a vertical movement in the reciprocations of the temple-head and having an acting point which works in the channel alongside the outer end of the adjacent temple-roll.

3. The combination with a spring-actuated slide-bar and roller-head adapted to be moved forward by the lay in beating-up, of a selvage-protecting device comprising a vertically swinging arm composed of a 70 socket-member mounted pivotally in connection with the slide-bar and roller-head; and a second member provided with a downturned point having a working position at the rear face of said roller-head, 75 said second member combined with the socket-member with capacity for adjustment of the point forward, rearward and laterally, and means for imparting vertical movement to the said arm or point.

In testimony whereof I affix my signature.
HECTOR LE DOUX.
